UNITED STATES PATENT OFFICE.

JOHN E. MEYERS, OF ALLIANCE, OHIO, ASSIGNOR TO THE BUCKEYE TWIST DRILL COMPANY, OF ALLIANCE, OHIO, A CORPORATION OF OHIO.

DRILL-TWISTING METHOD AND MACHINE.

Application filed May 16, 1921. Serial No. 469,824.

To all whom it may concern:

Be it known that I, JOHN F. MEYERS, a citizen of the United States, and resident of Alliance, in the county of Stark and State 5 of Ohio, have invented an Improved Drill-Twisting Method and Machine, of which the following is a specification.

The invention relates to means for twisting a drill from a straight bar; and the object of the improvement is to twist the drill 10 with a uniform pitch upon a straight axis, with an apparatus adjustable for twisting drills of various pitches, diameters and lengths.

15 The method of twisting a drill by turning means applied to the ends of the bar does not necessarily give a uniform pitch throughout the length, because of the varying physical conditions in different portions of the bar; and the method of twisting a drill by a series 20 of rotary dies operating on the bar in situ, involves an apparatus practically limited to twisting a drill of given dimensions and degrees of pitch, from which the twisted drill 25 must be removed by turning it as a screw from a threaded socket.

30 The present invention contemplates the use of adjustable dies successively operating upon adjacent sections of the bar, which moves intermittently endwise intermediate the successive twisting operations, following which it drops endwise from the dies.

35 The improved method and a preferred form of machine for twisting a drill, are illustrated in the accompanying drawings forming part hereof, in which—

Figure 1 is a front elevation of the machine, with the guide bar broken away;

Fig. 2, a side elevation of the same, with 40 the base broken away;

Fig. 3, a plan view of the twisting head in normal inoperative position;

Fig. 4, a section of the head on line 45 IV—IV, Fig. 3;

Fig. 5, an enlarged section of the twisting head on line V—V, Fig. 3, showing the guide bar and dies in side elevation;

Fig. 6, a similar view showing the guide bar in front elevation;

50 Fig. 7, an under side view of the rotary plate, broken away in one side to show die adjusting screws;

Fig. 8, a front edge elevation of the rotary plate;

Fig. 9, a section of same on line IX—IX, 55 Fig. 7 and 8;

Fig. 10, a detached perspective view of one upper or twisted die;

Fig. 11, a plan view of the stationary base plate, broken away in one side to show die 60 adjusting screws;

Fig. 12, a front edge elevation of the base plate;

Fig. 13, a section of same on line XIII—XIII, Figs. 11 and 12; 65

Fig. 14, a detached perspective view of one lower or stationary die;

Fig. 15, a plan view of the twisting head showing the rotary plate initially turned for receiving the drill blank to be stopped 70 by the holding dies;

Fig. 16, a fragmentary plan of the twisting dies showing in section the initial position of a drill blank;

Fig. 17, a fragmentary plan of the stationary dies, showing in section the initial position of a drill blank; 75

Fig. 18, a fragmentary section on line XVIII—XVIII, Fig. 15, showing the dies and drill blank in elevation; 80

Fig. 19, a plan view of the twisting head with the rotary plate turned to the return stop, and showing a bar in section therein;

Fig. 20, a fragmentary section on line XX—XX, Fig. 19, showing the dies and 85 blank in elevation, and illustrating in full lines, the initial twist given to the lower end of the bar, and in broken lines, the position of the bar after a full twist has been given and the bar dropped down for a second twisting operation;

Fig. 21, a plan view of the twisting head with the rotary plate turned to the twisting stop and showing a blank in section;

Fig. 22, is a fragmentary section on line 95 XXII—XXII, Fig. 21, showing the dies and blank in elevation, with the lower end section of the blank fully twisted; and

Fig. 23, a similar section showing the entire blank twisted to the base of the straight 100 flute portion thereof.

Similar numerals refer to similar parts throughout the drawings.

The machine may be mounted on a pedes-

tal 1, and comprises a base plate 2, and a rotary plate 3 upon which is preferably mounted a standard 4 having an adjustable bracket 5 thereon for a guide bar 6.

5 The base plate 2 is secured upon a support, which may be the pedestal, and as shown in Fig. 11, and is preferably in the form of a square block with raised corners 7 forming a circular recess 8 for receiving 10 the rotary plate 3.

The rotary plate 3 is preferably formed circular with a bottom flange 9 fitting in the circular recess of the base plate, over which flange are extended corner plates 10, secured 15 by cap screws 11 on the raised corners 7 of the base plate; which corner plates serve to hold the rotary plate in the bearing seat formed by the base plate, in which it is adapted to be freely rotated.

20 The twisting dies 12 are located in a diametric channel 13 provided in the under side of the rotary plate, in which channels the dies may be adjusted to and from the center of the plate by means of screws 14 25 and 15, as shown in Fig. 7.

One lateral half of the end of each die is cut away at 16 to give clearance for the corresponding half of a drill blank 17 and a laterally inclined facet 18 is formed on the 30 other side on the end of the die, which is adapted to abut the flat face 19 in the corresponding side of the drill blank 17, as shown in Figs. 16, 19, and 21. The upper and lower edge 20 of each facet 18 is preferably 35 beveled so as to present an obtuse corner, and the upper beveled edge serves to guide the end of the blank into the interval between the dies.

The twisting dies are adjusted for use, so 40 that the interval between the protruding edges 21 in the middle of each die will be substantially the same as the thickness of the drill blank in its median line. The width of the dies is equal to the outside diameter of 45 the largest drill blank for which the machine may be used; and it is evident that the machine can be operated for twisting drill blanks of less diameter as shown in the drawings.

50 A central aperture 22 is provided in the rotary plate above the twisting dies, in which is set a bushing 23 having an internally beveled or rounded upper edge and an inside diameter for receiving the outside diameter of the drill blank and guiding the same to properly enter between the twisting dies. Although the use of such a bushing is not essential, the insertion of drill blanks into the twisting head is facilitated by the 55 use of different bushings corresponding to the different diameters of drill blanks which may be twisted in the machine.

The stationary dies 24 are likewise located in a diametric channel 25 in the upper

side of the base plate; in which channel the 65 dies may be adjusted to and from the center of the disk by means of screws 14' and 15', as shown in Fig. 11.

One lateral half of the end of each stationary die is cut away at 26 to give clearance 70 for the corresponding half of the drill blank 17, and a laterally inclined facet 27 is formed on the other side of the end of the stationary die, which facet is also inclined downward and forward from the upper face 75 to the lower face of the die, and the facet is rounded adjacent to the lower face of the die so as to present a blunt edge 28 to impinge the corresponding flat face 19 in one side of the drill blank.

80 The stationary dies are adjusted for use, so that the interval between the protruding corners 29 in the middle of each die will be substantially the same as the thickness of the drill blank in its median line; and the 85 width of the dies is equal to the outside diameter of the largest drill blank for which the machine may be used, so that the machine can be operated for twisting drill blanks of less width, as shown in the drawings.

90 A central aperture 30 is provided in the base plate below the stationary dies, through which a twisted drill is adapted to be discharged downward; and an inclined chute 31 may be provided in the hollow of the 95 pedestal for delivering a twisted drill through an opening 32 in one side wall of the pedestal.

99 A straight drill blank may be entered into the machine by inserting it manually 100 through the guide bushing 22; and it is preferable to use the weighted guide bar 6, mounted for endwise sliding in the guide-way 33 in the bracket 5; which bracket may be secured at different heights on the standard 4 by means of a cap screw 34 extending through the slot 35 in the depending portion 36 of the bracket.

110 A guide head 37 is formed or secured on the lower end of the guide bar, which guide head is provided with a downwardly facing conical socket 38 which is adapted to receive and rest upon the upper end of a drill blank for the purpose of centering and holding it in upright position; and a handle 115 weight 39 is formed or secured on the upper end of the guide bar, by means of which it may be raised and lowered. The weight of the handle supplements the weight of the drill blank and the guide bar, and serves 120 to yieldingly press the drill bar downward by the action of gravity or a manual pressure during the twisting operation.

125 A longitudinal groove 40 is provided in the one side of the guide bar, and a communicating annular groove 41 is provided near the lower end of the bar; which grooves are adapted to receive a screw detent 42 in

the guide bracket 5. By these means the bar may be held in elevated position by turning it with the detent in the annular groove to one side of the longitudinal groove; and 5 the bar may be moved freely upward and downward by turning it so that the detent will operate in the longitudinal groove.

A handle 43 is secured to the top of the 10 rotary plate 3 by means of which the same may be turned; and a series of set screws 44 are provided in the rim of the disk, in a plane above the corner plates 10, which screws are adapted to be turned outward to form stops for engaging a spring plunger 15 detent 45, mounted on one of the corner plates, for limiting the rotation of the disk one way or another in the operation of the machine.

Preliminary to the twisting of a drill 20 blank, the same is heated in the usual manner to a forging temperature, before entering it into the twisting machine.

The normal inoperative position of the 25 rotary plate illustrated in Figs. 1 to 13 inclusive of the drawings, is such that the twisting dies are in alignment with the stationary dies so that a drill blank can pass endwise between all the dies; and for the purpose of setting the machine for receiving 30 a drill blank for the twisting operation, the rotary plate is slightly turned in one direction, which may be anticlockwise, to an initial position as shown in Fig. 15, which is fixed by turning out one of the set screws to 35 form a stop 44^a. This initial rotation slightly turns the twisting dies so that a drill blank cannot pass between the stationary dies.

When the rotary plate has been turned to initial position, as shown in Fig. 15, the 40 guide bar is raised and the lower end of a drill blank 17 is inserted downward through the guide bushing 23, and between the twisting dies 12, as shown in Fig. 16, until the diagonally opposite edges of the blank impinge and rest upon the rounded edge portions 28 of the stationary dies; as shown in 45 Figs. 17 and 18.

With the drill blank in the initial position, the detent 45 is pulled outward to clear the 50 initial stop 44^a, and the rotary plate is further turned in the same anticlockwise direction by the handle 43, until a stop 44^b has cleared the spring detent, which is then released to spring into the path of the stops, as 55 shown in Fig. 19, which figure shows the position of the parts when set screw 44^b serves as a return stop for the drill bar in a subsequent stage of the twisting operation.

At this point in the initial turning of the 60 rotary plate, the lower end of the drill bar has been twisted somewhat as shown in full lines in Fig. 20; the twisting being done by the turning of the twisting dies against the diagonally opposite sides of the drill blank

at a point above its lower end, which lower 65 end is held from turning by the bearing of the stationary dies against the directly opposite sides of the end of the blank.

The illustration of this stage of the 70 twisting operation is not intended to indicate that the turning of the rotary plate is stopped at this point. In the operation of the machine, the initial anticlockwise rotation of the plate is continued without stopping until the detent 45 is impinged by the stop 44^c, the particular location of which is determined by the pitch it is desired to give to the twist of the drill, thereby stopping the initial turning of the 75 rotary plate at the time the parts are in position as shown in Fig. 21, and the lower end section of the drill, below the twisting dies, has been given the full amount of twist intended for the drill, as shown in Fig. 22.

The rotary plate is then turned in the reverse or clockwise direction until the detent 80 45 is impinged by the return stop 44^b, as shown in Fig. 19, and during this operation the drill blank drops by the yielding action of gravity directly downward, by a sliding 85 of the twisted faces upon the inclined facets of the stationary dies, as the bar is being yieldingly turned by the reverse movement of the twisting dies; the position of the drill bar at the end of the first return rotation of 90 the plate 3 being shown in broken lines in Fig. 20.

As the reverse rotation of the plate 3 has been stopped before it returns to normal position, the downward movement of the drill 95 blank is stopped by a bearing of a twisted portion of the bar upon the edges of the stationary dies; and each succeeding section of the drill blank is then twisted in the same manner as described for the twisting of the 100 lower end section, which is accomplished by merely repeating the anticlockwise turning of the rotary plate until the detent is impinged by the stop 44^c followed by a clockwise rotation of the plate until the detent is 105 impinged by the return stop 44^b, as above described.

The operation of the machine for the 110 twisting of a drill is facilitated by the use of the guide bar which rests upon the upper 115 end of the drill blank, and not only centers the same during the twisting operation, but supplements the weight of the drill blank in causing it to move yieldingly downward each time the plate 3 is reversely rotated in 120 clockwise direction.

The flat facets on the ends of the twisting dies serve to prevent any bending of the 125 drill blank above the lower edges of the facets; and when a sufficient number of sections of the drill have been successively twisted to form a drill of the desired length, the upper ends of the remaining straight

portion 46 comprising the straight flute end of the drill may have dropped downward so that the guide head 37 will rest upon the guide bushing 23 as shown in Fig. 23; whereupon the rotary plate is reversely turned clockwise, back to the normal position shown in Fig. 3, which permits the twisted drill to drop downward freely from the dies and to be delivered at one side of the machine.

10. The dies illustrated in the drawings are designed for use in twisting a drill blank having longitudinal shallow V-flutes in each side to form a double dove-tail section, although it will be understood that the use of the machine is not limited to a flattened or fluted drill bar of this specific section.

15. An adjustment of the dies can be readily made for twisting drill blanks of various diameter, and the shape of the dies can be varied to conform to drill blanks of various shapes of cross section. There is no limit to the length of drill blanks which can be twisted by the improved machine, and the 20 machine can be operated to twist the drill with any desired pitch by merely changing the position of the twisting and return stops, which is readily done by using different set screws for such stops.

25. 30. The operation of the machine in successively twisting comparatively short sections of the blank in exactly the same manner, insures a uniformity of the twist throughout the length of the drill; and the guiding action of the machine insures that all the 35 twists will be made in exactly the same axis, thereby certainly producing a drill free of lateral deflections.

35. It is evident that the method and machine 40 illustrated and described herein, may be used for twisting reamers, and other like tools, as well as drills; and the use of the term drill in the description and claims is intended to be inclusive of such other tools.

45. I claim:—

1. The method of twisting a drill blank which consists in successively twisting short sections of the blank and intermittently moving the blank endwise between successive 50 twisting operations.

2. The method of twisting a drill blank which consists in successively twisting short sections of the blank and intermittently moving the blank endwise by a yielding 55 pressure between successive twisting operations.

3. The method of twisting short sections of the drill blank by adjacent dies relatively 60 rotary and stationary, reversely rotating the blank between successive twisting opera-

tions, and yieldingly moving the blank endwise during the reverse rotation of the same.

4. A drill blank twisting machine comprising rotary dies and adjacent stationary dies for twisting an intervening section of a 65 blank extended through the dies, and yielding pressure means for moving the twisted section between the dies through the stationary dies.

5. A drill blank twisting machine comprising a base plate and rotary plate, adjacent dies in the plates for twisting an intervening section of a blank extended through the dies, and yielding pressure means for moving the blank endwise. 70

6. A drill twisting machine comprising a base plate and a rotary plate, dies in the plates each engaging one lateral half only of the drill blank, and variable means for stopping the turning of the rotary plate in 75 opposite directions.

7. A drill twisting machine comprising a base plate and a rotary plate each having central apertures, dies in the plates each engaging one lateral half only of the drill blank, and a bushing in one of the apertures 80 for guiding the blank.

8. A drill twisting machine comprising a base plate and a rotary plate, dies in the plates each engaging one lateral half only of 85 the drill blank and a guide bar bearing on the end of the blank.

9. A drill twisting machine comprising a base plate and a rotary plate, dies in the plates each engaging one lateral half only 90 of the drill blank, and a guide bar bearing on the end of the blank with a socket for centering the blank.

10. A drill twisting machine comprising a base plate and a rotary plate, and dies in the 100 plates each engaging one lateral half only of the drill blank, the dies in one plate having flat facets engaging the corresponding side of the blank.

11. A drill twisting machine comprising a base plate and a rotary plate, and dies in the plates each engaging one lateral half only 105 of the drill blank, the engaging side of the dies in one plate having inclined facets facing the dies in the other plate.

12. A drill twisting machine comprising a base plate and a rotary plate, and dies in the plates each engaging one lateral half only 110 of the drill blank, the engaging side of the dies in one plate having inclined facets facing the dies in the other plate with blunt edges impinging the corresponding sides of the blank.

JOHN F. MEYERS.
